CORE WRAPPING MACHINE

Edward Watchorn, Aldwych, London, England,
assignor to Western Electric Company, Incorporated, New York, N. Y., a corporation of New York

Application September 11, 1929, Serial No. 391,873, and in Czechoslovakia September 15, 1928

6 Claims. (Cl. 117—41)

This invention relates to improvements in or appertaining to machines for assembling paper strips about a metallic core, and more particularly to machines for making insulated electrostatic screens for use in electric communication cables.

It is customary in the present cable systems, in which certain circuits grouped together for transmission in one direction are assembled at one part of the cable, and circuits for transmission in the opposite direction are grouped together in another part of the cable, to use an electrostatic screen between the two groups to prevent interference between them.

In quaded cables this screen is usually in the form of a quad, which may or may not be used for transmission but which cannot be used for 4 wire repeater operation. This is obviously rather uneconomical and moreover the structure of a quad is not the best design for screening purposes.

Other forms of screens have been used to replace the screening quad and the object of the present invention is to provide a machine for making an improved form of such separator screen, and by use of which the screen material may be manufactured in the form of a continuous ribbon having a special uniform structure hereinafter described.

According to the invention a machine comprises means for applying to a metallic ribbon, on one or both sides of it, a strip of paper, eventually to act as a separator, and means for causing the continuous movement of said ribbon and strip, and further means including forming dies for turning towards or away from the metal ribbon the edges of the paper strip, and a device for wrapping a binding tape about the metal ribbon and separator strips.

Other features of the invention will appear in the following description in which:

Fig. 1 is a side elevation of the machine.

Fig. 2 is a detailed plan to an enlarged scale of a guiding member shown in Fig. 1.

Fig. 3 is a side elevation of the parts shown in Fig. 2.

Fig. 4 is a part section on the line A—A of Fig. 2.

Fig. 5 is a part section on the line B—B of Fig. 2.

Fig. 6 is a cross section of a composite strip produced at a stage in the manufacture of the screen, and

Fig. 7 shows the final strip after leaving the machine.

On a bed 1 are supported the fixed bearings 2 and 3 of a hollow revolvable shaft 4, which car-

ries a driving pulley 5 for a head 6. A die 7 is mounted upon the bearing 2 at the end of the shaft 4 and through this die is drawn a metallic ribbon and one or more paper strips. The metallic ribbon is contained on the drum 8, the paper strips being contained on the drums 9 and 10. The strips from these drums are drawn through the die 7, the metallic ribbon being preferably situated between two paper strips, the motion being caused by means of the capstan 11 driven in any suitable manner and situated on the other side of a supporting die 12, carried on the bed 1, as shown. A suitable take-up reel 13 is provided. The bearing 2 is a bearing for the shaft 4 in which the shaft revolves but the bearing 2 also carries 70 and supports the non-revolving steel bar 14 which extends completely through the shaft 4 and the head 6 and carries the member 15 which is shown in further detail in Figs. 2, 3, 4 and 5. Two brackets 16 of the member 15 are secured to the 75 bar 14 and carry guide members 17 as shown in Fig. 4. These guide members are separated by a small distance sufficient to enable the metallic ribbon *a* to pass between them. It will be seen from Fig. 2 that the members 17 are reduced in 80 width and have thin edges converging towards the output end. The width at the input end as shown in Fig. 4 is sufficient to allow the paper strip 6 to enter the passage provided and owing to the curvature of the guide members and its 85 converging form, the edges of the strip are turned over as shown in Fig. 5, so that on withdrawal from the member 15 the ribbon *a* has on either side of it a paper strip shaped substantially as shown in Fig. 6 with the edges folded 90 under. The members 17 constitute means for turning the edges of the paper strip under toward the metal ribbon, in other words, doubling the edges back upon the paper strip; similar results can be accomplished to a degree by turning 95 the edges of the paper strip away from the metal ribbon and doubling them back upon the paper strip. At the end of the bar 14 a smoothing die 20 is preferably provided, which presses the paper strips *b* upon the metallic ribbon *a*. Mounted on the head 6 is a reel 18 carrying a paper pad 19. When the head is rotated simultaneously with rotation of the capstan 11 the paper tape *C* from the pad 19 is wrapped about the composite strip 100 from the output of the die 20, the strip being supported by the projection 21 of the bar 14, so that a final structure substantially as shown in Fig. 7 is produced. Usually it is preferable to provide 105 a paper strip *b* on both sides of the metallic ribbon 110

bon *a* but if desired one paper strip only may be provided.

It is, of course, obvious that many of the constructional features of the above machine may be varied without altering its function.

What is claimed is:

1. A machine for assembling paper strips about a metallic core, comprising in combination means for placing on one or both sides of a metallic ribbon a strip of paper, eventually to act as a separator, means for causing a continuous longitudinal movement of said ribbon and strip and further means including a guide member for doubling back upon itself towards or away from the metal ribbon the edges of the paper strip, and a device for wrapping a binding tape about the metal ribbon and separator strip.
2. A machine according to claim 1, characterized in this, that said guide member comprises two curved and convergent channels with an opening therebetween for the passage of the metal ribbon.
3. A machine in accordance with claim 1, in which a smoothing die lies beyond the said further means and is traversed by the core and strip.
4. A machine according to claim 1, in which a rigid support lies beyond the said further means for supporting the core and strip at the point of application of the binding tape.

5. A machine for making a strip with another strip laid parallel thereto upon a side thereof with folded down edges, comprising two spools for carrying the respective strips, guide means through which the strips pass, said guide means having surfaces curved to double back upon itself the edges of the strip to be folded, mechanism for pulling the two strips through the guide means, a head revolving around the strips for applying a binding tape to the laid together strips, and mechanism for revolving the head.

6. A machine for laying a long, flexible strip of material upon another strip of material with the edges of the flexible strip folded in a manner to make the edge portions double upon a side of the other strip, which comprises means for laying the strips together, means for drawing them parallel to one another in a longitudinal direction, a shaping die for the flexible strip lying in the path of its longitudinal motion, said die having an inlet opening wide enough to receive the flexible strip in a position not more than slightly curved in cross section, and a body and an end portion narrowed and shaped to double the edges of the flexible strip back upon the body of the flexible strip.
